ZONE CONTROL SYSTEM

John L. Harris, Minneapolis, Minn., assignor to
 Minneapolis-Honeywell Regulator Company,
 Minneapolis, Minn., a corporation of Delaware

Application April 17, 1939, Serial No. 268,184

20 Claims. (Cl. 236—91)

This invention relates to a temperature control system for a building which is divided in zones for conditioning purposes.

In conventional systems of this type steam or other temperature changing fluid is conducted from a suitable source to heat exchangers in the various zones and a thermostatically controlled zone valve or equivalent means regulates the supply of steam to the heat exchangers of each zone for maintaining desired temperature conditions in each zone. Although such a system usually provides accurate temperature control, undesirable conditions often arise by reason of more than one zone valve opening or closing at substantially the same time.

In the case where the source of steam is a boiler controlled by suitable pressure controls, opening of more than one zone valve at substantially the same time places a substantially instantaneous large load on the boiler whereupon the steam pressure decreases quite an extent before the boiler can recover and maintain the desired steam pressure. This decrease in steam pressure may be so great as to prevent the proper distribution of steam throughout the system with a result that the heating system does not maintain accurate temperature conditions in the various zones. Closing more than one zone valve at substantially the same time decreases substantially instantaneously the load on the boiler whereupon the boiler pressure increases to quite an extent. This increase in steam pressure may be so great as to cause popping of the boiler through its safety blow-off valves which is not conducive of economical operation. It is well established that a boiler may be operated most efficiently when the load on the same is maintained relatively constant and if the load is caused to vary rapidly as it will under the above conditions, the efficiency of operation of the boiler is accordingly reduced.

In the case where the source of steam is a central power plant or district steam supply system, substantially simultaneous opening or closing of the zone valves will vary greatly the demand for steam in the same manner as outlined above. Inasmuch as the cost of steam not only depends upon the amount of steam consumed but upon the rate at which it is consumed, the above system is relatively expensive to operate under these conditions. Further, it is not desirable to cause the steam pressures in the district steam supply system to fluctuate greatly which the above system might easily do.

The primary object of this invention is to avoid 55 A pressure controller generally designated at

the above undesirable conditions which are inherent in a conventional zone heating system. In carrying out this invention means are provided for preventing opening of the zone valves when the steam pressure decreases below a desired value and for preventing closing of the zone valves when the steam pressure is above a desired value until such time as the steam pressure is restored to the desired normal operating values. 10 This effectively prevents large fluctuations or surges in steam pressure whereupon the heating system may be operated more satisfactorily and economically.

A further object of this invention is to provide means operative when the steam pressure is restored to the desired normal value for opening or closing first that zone valve whose temperature responsive means first demanded opening or closing thereof. By reason of this feature proper 20 proportioning of steam to the various zones is at all times assured.

This improvement, which maintains the steam pressure within relatively narrow limits, has an added advantage when applied to a system 25 wherein the zone valves are controlled by an outdoor controller of the type shown and described in Patent No. 2,065,835 granted to D. G. Taylor on December 29, 1936. By maintaining the steam pressure within relatively narrow 30 limits the amount of heat supplied to the zone in a predetermined time interval may be quite accurately gaged and may therefore be readily balanced against the amount of heat supplied to the outdoor controller. This feature also forms 35 an object of this invention.

Other objects and advantages will become apparent to those skilled in the art upon reference to the accompanying specification, claims and drawing.

For a more thorough understanding of this invention reference is made to the accompanying single sheet of drawing which diagrammatically illustrates the control system of this invention as applied to a multiple zone heating 45 system.

The building or other enclosure to be conditioned, not shown, may be divided into three zones, A, B, and C, each zone being provided with the usual heat exchangers, steam traps, piping 50 connections and orifices which are conventional in these systems. The source of temperature changing fluid such as steam may be a steam boiler 10 fired by a coal stoker, oil burner, gas valve or other similar device designated at 11.

13 may control the operation of the firing device to maintain the boiler pressure at desired values. The pressure controller 13 may comprise a bellows 14 connected by a pipe 15 to the boiler 10 for operating a lever 16 against the action of an adjustable tension spring 17. The lever 16 in turn operates a mercury switch 18 and for purposes of illustration it is assumed that the switch 18 is moved to a closed position when the boiler pressure decreases to 4 lbs. and is moved to an open position when the boiler pressure increases to 6 lbs. Power is supplied to the firing means 11 by means of line wires 19 and 20 leading from some source of power, not shown. When the pressure on the boiler decreases to 4 lbs. a circuit is completed from the line wire 19 through the mercury switch 18 and firing device 11 back to the other line wire 20 to place the firing means 11 in operation. When the boiler pressure increases to 6 lbs. the above circuit is opened and the firing means 11 is stopped. In this manner the steam pressure in the boiler 10 is maintained between 4 lbs. and 6 lbs.

A header 22 supplies steam from the boiler 10 to risers 23, 24, and 25 which extend to the heat exchangers in zones A, B, and C, respectively. The supply of steam to zone A is controlled by a valve 26 operated by a two position electric motor 29 and the supply of steam to zones B and C may be controlled by valves 27 and 28, respectively, which in turn are controlled by two position electric motors 30 and 31. Thus the supply of steam to the various zones is individually controlled by zone valves.

The motors of the zone valves 26, 27, and 28 are respectively controlled by relays generally designated at 33, 34, and 35. The relays 33, 34, and 35 are in turn controlled by temperature responsive controllers 36, 37 and 38, respectively, the controller 36 being associated with zone A and the controllers 37 and 38 being associated respectively with zones B and C. When the temperature responsive controller 36 of zone A demands heat, the relay 33 is operated to open the zone valve 26 to supply heat to zone A and when the temperature responsive controller 36 becomes satisfied the relay 33 is operated to close the zone valve 26. In a like manner the temperature responsive controllers 37 and 38 of zones B and C operate through their relays 34 and 35 to open and close the zone valves 27 and 28 which control the supply of steam to the heat exchangers of zones B and C. A relay generally designated at 39 controls all of the relays 33, 34, and 35 to prevent operation of the relays when any zone valve is opening or closing. A pressure controller generally designated at 40 also controls all of the relays 33, 34, and 35 to prevent operation of the relays and hence operation of the zone valves whenever the steam pressure is above or below predetermined values.

Although the temperature responsive controller 36 of zone A may be a conventional thermostat responding to the temperature within zone A, it is shown for purposes of illustration to be an outdoor controller of the type shown and described in Patent No. 2,065,835 granted to D. G. Taylor on December 29, 1936. This temperature responsive controller is located outside of the building immediately adjacent the zone which it controls so that it is responsive to the same atmospheric conditions including temperature, wind, and solar radiation that affect its associated zone. The temperature responsive controller may comprise a mass in the form of a

metallic block 42 in which is located a thermostatic element 43. The thermostatic element 43 responds to the temperature of the block 42 and operates contacts 44 and 45 with respect to adjustable stationary contacts 46 and 47, respectively. An electric heater 48 is intimately associated with block 42 for heating the same and this heater has sufficient capacity to maintain the block 42 at a desired temperature regardless of outside atmospheric conditions. The block 42 may be suitably mounted on a base 49 and the entire mechanism may be enclosed by a cover 50 for protecting the same against the elements. For purposes of illustration it is assumed that contacts 44 and 46 make and break at 70° and that the contacts 45 and 47 make and break at 65°. The temperature responsive controllers 31 and 38 of zones B and C are identical to the temperature responsive controller 36 of zone A and therefore a description of these temperature responsive controllers is not deemed necessary.

The relay 33 controlled by the temperature responsive controller 36 of zone A may comprise an operating coil 52 for operating switch arms 53, 54, and 55. When the operating coil 52 is energized, the switch arms 53, 54, and 55 are moved into engagement with contacts 56, 57, and 58, respectively, and when the operating coil 52 is deenergized the switch arms 53, 54, and 55 are moved out of engagement with their respective contacts by means of springs, gravity or other means not shown and the switch arm 55 is moved into engagement with a stationary contact 59. The relay 33 may also include a step-down transformer 60 having a secondary 61 and a primary 62 connected by wires 63 and 64 across line wires 65 and 66 leading from some source of power, not shown. The step-down transformer 60 is utilized for supplying power to the control circuits of the relay 33 as well as for supplying power to the heater 48 of the outdoor controller 36. The construction of the relays 34 and 35 is exactly the same as the relay 33 and therefore a description of these relays is not considered necessary.

The relay 39 may comprise an operating coil 70 for operating switch arms 71, 71B, 71C, and 72C. When the operating coil 70 is energized the switch arms 71, 71B, and 71C are moved into engagement with contacts 73, 73B, and 73C and the switch arms 72, 72B, and 72C are moved out of engagement with contacts 74, 74B, and 74C. When the operating coil 70 is deenergized the switch arms 71, 71B, and 71C are moved out of engagement with their respective contacts and the switch arms 72, 72B, and 72C are moved into engagement with their respective contacts by means of springs, gravity, or other means, not shown.

The pressure controller 40 may comprise a bellows 78 connected by a pipe 79 to the header 22 for operating a lever 80 against the action of an adjustable tension spring 81. The lever 80 operates a shaft 82 upon which are mounted thermostatic elements 83, 84, 83B, 84B, 83C, and 84C which in turn carry mercury switches 85, 86, 85B, 85C, and 86C, respectively. The switches 85, 85B, and 85C are normally open as shown and the switches 86, 86B, and 86C are normally closed as shown. Upon a rise in steam pressure the mercury switches are tilted in a counter-clockwise direction by the shaft 82 as indicated by the arrow designated "rise" and upon a drop in pressure these mercury switches are tilted in a clockwise direction as indicated by

the arrow designated "drop". For purposes of illustration it is assumed that when the pressure drops to 2 lbs., the mercury switches 86, 86B, and 86C are opened and when the pressure rises to 8 lbs. the mercury switches 85, 85B, and 85C are closed. Between these pressure values the mercury switches assume the positions shown in the drawing. The thermostatic elements 83, 83B, and 83C are provided with heaters 87, 87B, and 87C, respectively, and when the heaters are energized they tend to flex the thermostatic elements to the left as indicated by the arrow designated "H". The thermostatic elements 84, 84B, and 84C are provided with heaters 88, 88B, and 88C and when these heaters are energized they operate to flex the thermostatic elements to the right in the direction indicated by the arrow designated "H".

Power is supplied to the two position electric motors 29, 30, and 31 by means of line wires 90 and 91 leading from some source of power, not shown. The power terminals 92 and 93 of these two position motors are connected in parallel across the line wires 90 and 91. The motors 29, 30, and 31 are of the two position type which require power only when the motors are being operated from a closed position to an open position or from an open position to a closed position. When the motors are stationary, that is, either open or closed, they do not require power. The operating coil 70 of the relay 39 is connected in series with the power supply leading to the zone valve motors 29, 30, and 31 so that the operating coil 70 is energized when any of the zone valve motors are operating. The zone valve motors are provided with control terminals 94, 95, and 96 for controlling the operation thereof. When a circuit is completed across the control terminals 94 and 95 the zone valves are moved to closed position and when a circuit is completed across the control terminals 95 and 96 the zone valves are moved to open position.

With the parts in the position shown in the drawing a decrease in temperature in the outdoor controller 36 of zone A to 65° causes the contacts 44, 46 and 45, 47 to close to complete a starting circuit for the operating coil 52 of the relay 33. This starting circuit may be traced from the secondary 61 of the step-down transformer 60 through wires 100 and 101, contacts 46, 44, 45, and 47, wire 102, contact 74 and switch arm 72 of relay 39, wire 103, mercury switch 86 of the pressure controller 40, wires 104 and 105, operating coil 52 and wire 106 back to the secondary 61. Completion of this starting circuit energizes the operating coil 52 to move the switch arms 53, 54, and 55 into engagement with contacts 56, 57, and 58.

Movement of the switch arm 54 into engagement with the contact 57 completes a circuit from the secondary 61 through wire 108, contact 57, switch arm 54, wire 109, variable resistance 110, wire 111, heater 48 of the outdoor controller 36 and wire 112 back to the secondary 61. Completion of this circuit energizes the heater 48 to heat the outdoor controller 36 and the amount of heat supplied by the heater 48 to the outdoor controller 36 is determined by the variable resistance 110.

Movement of the switch arm 55 into engagement with the contact 58 completes a circuit from the control terminal 95 of the zone valve motor 29 through wire 115, switch arm 55, contact 58 and wire 114 to the control terminal 96. Completion of this circuit causes opening of the zone valve 26 for zone A. Heat is therefore be-

ing supplied to zone A as well as to the outdoor controller 36 for zone A.

Movement of the switch arm 53 into engagement with the contact 56 completes a main maintaining circuit for the operating coil 52 which may be traced from the secondary 61 through wires 100 and 101, contacts 46 and 44, thermostatic element 43, wire 117, contact 56, switch arm 53, wire 105, operating coil 52 and wire 106 back to the secondary 61. Completion of this main maintaining circuit maintains the operating coil 52 energized until such time as the temperature within the outdoor controller 36 increases to 70° to separate the contacts 44 and 46. When this occurs the operating coil 52 is deenergized to move the switch arms 53, 54, and 55 out of engagement with their associated contacts and to move the switch arm 55 into engagement with the contact 59. Movement of the switch arm 54 out of engagement with the contact 57 deenergizes the heater 48 of the outdoor controller 36. Movement of the switch arm 55 into engagement with the contact 59 completes a circuit from the control terminal 95 of the zone valve motor 29 through wire 115, switch arm 55, contact 59, and wire 119 to the control terminal 94. Completion of this circuit operates the valve motor 29 to close the zone valve 26 whereupon the supply of heat to zone A is interrupted. The operating coil 52 of the relay 33 cannot again be energized until such time as the temperature of the outdoor controller 36 decreases to 65° and when this occurs the above outlined sequence of operation again takes place. The outdoor controller 36 of zone A therefore operates the relay 33 to open the zone valve 26 for zone A and to energize the heater 48 of the outdoor controller 36 upon a demand for heat and when the demand for heat is satisfied the relay 33 is dropped out to close the zone valve 26 and to deenergize the heater 48. By properly adjusting the variable resistance 110 the heat inputs to the outdoor controller 36 and to zone A may be proportioned in accordance with the heat losses from the outdoor controller and the zone whereby substantially constant temperatures are maintained within zone A as well as within the outdoor controller 36.

The construction and sequence of operation outlined immediately above in connection with zone A are the same for zones B and C and accordingly like reference characters have been utilized for like parts and wiring connections, the reference characters for zone B being designated B and the reference characters for zone C being designated C. It is therefore seen that the outdoor controllers 36, 37, and 38 control the operation of their associated zone valves 26, 27, and 28 to maintain desired temperature conditions in each zone.

As pointed out above when any zone valve is operating the operating coil 70 of the relay 39 is energized and as a result the switch arms 72, 72B, and 72C are moved out of engagement with their respective contacts 14, 14B, and 14C. It will here be noted that the starting circuit for energizing the operating coil 52 of the relay 33 passes in series through the switch formed by the switch arm 72 and the contact 14 of the relay 39. Hence when either zone valve 27 or 28 is operating it is impossible to pull in the relay 33 to open the zone valve 26. In a like manner the starting circuits for relays 34 and 35 pass through the switches formed by the contacts 14B and 14C and the switch arms 72B and 72C of the relay

39 so that these relays cannot be pulled in when any zone valve is operating. Accordingly after one zone valve has started to open it is impossible for any of the other zone valves to open until after that zone valve has been completely opened.

If now one of the zone valves should open and as a result the steam pressure drops to 2 lbs. to open the mercury switches 86, 86B, and 86C, it is impossible to open any of the other zone valves since the starting circuits for the operating coils 52 of the relays 33, 34, and 35 also extend through these mercury switches. Accordingly when the steam pressure decreases below, illustratively, 2 lbs., it is impossible to open any of the zone valves until such time as the steam pressure is restored to substantially the 2 lb. pressure value to close the switches 86, 86B, and 86C. Thus, when the steam pressure is low, opening of additional zone valves with a consequent further reduction in steam pressure is prevented. This arrangement therefore tends to maintain the steam pressure within desired limits.

The heater elements 88, 88B, and 88C, which upon energization flex the thermostatic elements 84, 84B, and 84C to the right, are connected in parallel with the electrodes of the mercury switches 86, 86B, and 86C, respectively. These heating elements have sufficient resistance that they will not allow the operating coil 52 of the relays 33, 34, and 35 to be sufficiently energized to pull in the relays if the other switches demand pulling in of the relays. Assume now that the controller 37 of zone B has called for heating and has opened its zone valve 27 with a result that the steam pressure has dropped below the 2 lb. value to open the switches 86, 86B, and 86C. Also assume that the thermostatic controller of zone C is satisfied with its zone valve 28 closed but that while the steam pressure is below 2 lbs. the controller 38 of zone A demands heat. The zone valve 26 of zone A cannot be opened at this time inasmuch as the mercury switch 86 is open. However current will flow through the heater element 88 and tend to move the mercury switch 86 toward a closed position. When the steam pressure starts to rise, the switch 86 will therefore close before the mercury switch 86C closes and therefore, even though controller 38 of zone C then begins to call for heat, the zone valve 26 of zone A will open before the zone valve 28 of zone C will open. In other words when one zone valve has opened with a resultant decrease in steam pressure below the 2 lb. value, the next zone valve which would be opened will be determined by the time at which its controller demands heat. Illustratively, if the controller 36 of zone A should demand heat before the controller 38 of zone C demands heat the zone valve 26 of zone A will open before the zone valve 28 of zone C opens. By reason of this arrangement the proper proportioning of steam to the various zones of the building will be assured and no zone will ever be starved of steam by any other zone.

Assume now that the zone valves 26 and 27 of zones A and B are opened, that the controller 37 of zone B becomes satisfied whereupon the zone valve 27 starts closing and that the controller 36 of zone A becomes satisfied while the zone valve 27 of zone B is closing. Ordinarily the zone valve 26 of zone A would close but it is maintained open by a first auxiliary maintaining circuit until such time as the zone valve 27 of zone B becomes completely closed. As was pointed out above when the zone valve 27 of zone B is oper-

ating, the operating coil 10 of the relay 39 is energized whereupon the relay 39 is pulled in to move the switch arm 11 into engagement with the contact 73. This first auxiliary maintaining circuit may be traced from the secondary 61 through wires 100, 121, contact 73, switch arm 11, wire 122, contact 56, switch arm 53, wire 105, operating coil 52 and wire 106 back to the secondary 61. Completion of this first auxiliary maintaining circuit maintains the relay 33 pulled in to prevent closing of the zone valve 26 while the zone valve 27 is closing. The other zone valves are prevented from closing under these conditions in a like manner. The relay 39 therefore prevents any zone valve from closing while any other zone valve is in operation.

If now one of the zone valves should close with the result that the steam pressure should rise to 8 lbs. the mercury switches 85, 85B, and 85C of the pressure controller 40 are closed and closure of these switches completes a second auxiliary maintaining circuit for the relays 33, 34, and 35. Referring to zone A this second auxiliary circuit may be traced from the secondary 61 through wires 100, 121, and 124, mercury switch 85, heater 87, wires 125 and 122, contact 56, switch arm 53, wire 105, operating coil 52, and wire 106 back to the secondary 61. Completion of this second auxiliary maintaining circuit maintains the operating coil 52 energized to prevent closure of the zone valve 26 whenever the steam pressure is above 8 lbs. The operation in this respect is the same for zones B and C as it is for zone A. Accordingly whenever the steam pressure rises above 8 lbs. it is impossible to close any zone valve when its temperature responsive controller becomes satisfied until such time as the steam pressure decreases to substantially 8 lbs.

It is here noted that while the heater 87 is in series with the mercury switch 85 it is in effect in parallel with the contacts 44 and 46 of the controller 36 so that when the contacts 44 and 46 are closed the heater 87 is not energized. However when the relay 33 is pulled in and the contacts 44 and 46 separate the heater 87 becomes energized. In other words, when any controller becomes satisfied while the steam pressure is above 8 lbs. the heater 87 of that zone becomes energized to urge the mercury switch 85 associated therewith toward an open position. Thus, as the pressure decreases towards 8 lbs., the mercury switch to close first depends upon which heater was energized first and since the energization of the heater begins when the temperature responsive controllers become satisfied, then the mercury switches are closed in an order corresponding to the times at which the temperature responsive controllers become satisfied. Accordingly, if the steam pressure be above 8 lbs. and the controller 36 of zone A becomes satisfied before the controller 37 of zone B, then the zone valve 26 of zone A will close before the zone valve 27 of zone B. This effectively prevents overheating of any zone by insuring that the zone temperature controller which becomes satisfied closes its zone valve first.

The operation of the complete system may be summarized briefly as follows: the zone valves controlling the supply of steam or other temperature changing fluid are individually opened and closed by their temperature responsive controllers to maintain desired temperature conditions in each zone. While any zone valve is operating either to an open position or to a closed

position it is impossible to operate the other zone valves whereby substantially simultaneous opening or closing of more than one zone valve is prevented. This tends to maintain the steam pressures within desired limits. If the steam pressure should decrease below a desired value by reason of a zone valve opening it is impossible to open any other zone valve until such time as the steam pressure is restored to substantially that desired value. If the steam pressure should rise above a desired value by reason of a zone valve closing it is impossible to close any of the other zone valves until such time as the steam pressure is restored to substantially that desired value. By reason of this arrangement the steam pressure is maintained within desired limits at all times whereby large fluctuations or surges in steam pressure are effectively prevented. Satisfactory and economical operation of the heating system is therefore assured. In order to prevent underheating in any zone provision is made for opening the zone valves in an order corresponding to the time at which the zone temperature controllers call for heat and likewise to prevent overheating in any zone the zone valves are closed in an order depending upon the time at which the zone temperature responsive controllers become satisfied.

While for purposes of illustration one form of this invention has been disclosed, other forms thereof may become apparent to those skilled in the art upon reference to this disclosure and therefore this invention is to be limited only by the scope of the appended claims and prior art.

I claim as my invention:

1. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, temperature responsive means associated with each zone for controlling the regulating means of that zone to maintain desired temperature conditions in the various zones, and means associated with the regulating means and responsive to a condition of the temperature changing fluid affected by the demand for said fluid, said means being operative upon said condition varying undesirably in one direction by reason of operation of one of said regulating means in one manner to prevent immediate operation of another of said regulating means in the same manner, without affecting the operation of the regulating means which has already operated in that manner.

2. In a temperature control system for a building having a plurality of zones to be conditioned the combination of, a source of temperature changing fluid, means for supplying temperature changing fluid from said source to the zones of the building for conditioning the same, regulating means for each zone for increasing and decreasing the supply of temperature changing fluid to its associated zone, temperature responsive means associated with each zone for controlling the regulating means of that zone to maintain desired temperature conditions in the various zones, and means associated with the regulating means and responsive to the temperature changing ability of the temperature changing fluid, said means being operative when the temperature changing ability of the temperature changing

fluid decreases below a desired value to prevent operation of any of said regulating means to increase the supply of fluid to its zone, without affecting the operation of any regulating means which has already caused such an increase.

3. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, temperature responsive means associated with each zone for controlling the regulating means of that zone to maintain desired temperature conditions in the various zones, and means associated with the regulating means and responsive to the temperature changing capacity of the temperature changing fluid, said means being operative when the temperature changing capacity of the temperature changing fluid increases above a desired value to prevent operation of any of said regulating means to decrease the supply of fluid to its zone, without affecting the operation of any regulating means which has already caused such a decrease.

4. In a temperature control system for a building having a plurality of zones to be heated, the combination of, a source of steam, heat exchanger means in each zone, means for supplying steam from said source to the heat exchanger means of the various zones for heating the same, valve means for each zone for regulating the supply of steam to the heat exchanger means of that zone, temperature responsive means associated with each zone for opening and closing the valve means of that zone to maintain desired temperature conditions within the various zones, and means associated with the valve means and responsive to the pressure of the steam at said source for preventing opening of the valve means when the pressure of the steam decreases below a desired value without causing closure of said valve means if already open.

5. In a temperature control system for a building having a plurality of zones to be heated, the combination of, a source of steam, heat exchanger means in each zone, means for supplying steam from said source to the heat exchanger means of the various zones for heating the same, valve means for each zone for regulating the supply of steam to the heat exchanger means of that zone, temperature responsive means associated with each zone for opening and closing the valve means of that zone to maintain desired temperature conditions within the various zones, and means associated with the valve means and responsive to the pressure of the steam at said source for preventing closing of the valve means when the pressure of the steam increases above a desired value without causing opening of said valve means if already closed.

6. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, temperature responsive means associated with each zone for con-

trolling the regulating means of that zone to maintain desired temperature conditions in the various zones, means associated with the regulating means and responsive to the condition of the temperature changing fluid for preventing operation of the regulating means when the condition of the temperature changing fluid varies from desired values, and means operative when the condition of the temperature changing fluid is restored to the desired values for operating first that regulating means whose temperature responsive means first demanded operation.

7. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, temperature responsive means associated with each zone for controlling the regulating means of that zone to maintain desired temperature conditions in the various zones, means associated with the regulating means and responsive to the temperature changing capacity of the temperature changing fluid for preventing the regulating means from increasing the supply of temperature changing fluid when the temperature changing capacity of the temperature changing fluid decreases below a desired value, and means operative when the temperature changing capacity of the temperature changing fluid is restored to the desired value for operating first that regulating means whose temperature responsive means first demanded increasing of the supply of temperature changing fluid.

8. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, temperature responsive means associated with each zone for controlling the regulating means of that zone to maintain desired temperature conditions in the various zones, means associated with the regulating means and responsive to the temperature changing capacity of the temperature changing fluid for preventing the regulating means from decreasing the supply of temperature changing fluid when the temperature changing capacity of the temperature changing fluid increases above a desired value, and means operative when the temperature changing capacity of the temperature changing fluid is restored to the desired value for operating first that regulating means whose temperature responsive means first demanded decreasing of the supply of temperature changing fluid.

9. In a temperature control system for a building having a plurality of zones to be heated, the combination of, a source of steam, heat exchanger means in each zone, means for supplying steam from said source to the heat exchanger means of the various zones for heating the same, valve means for each zone for regulating the supply of steam to the heat exchanger means of that zone, temperature responsive means associated with each zone for opening and closing the valve means of that zone to maintain

desired temperature conditions within the various zones, means associated with the valve means and responsive to the pressure of the steam at said source for preventing opening of the valve means when the pressure of the steam decreases below a desired value, and means operative when the steam pressure is restored to the desired value for opening first that valve means whose temperature responsive means first demanded opening thereof.

10. In a temperature control system for a building having a plurality of zones to be heated, the combination of, a source of steam, heat exchanger means in each zone, means for supplying steam from said source to the heat exchanger means of the various zones for heating the same, valve means for each zone for regulating the supply of steam to the heat exchanger means of that zone, temperature responsive means associated with each zone for opening and closing the valve means of that zone to maintain desired temperature conditions within the various zones, means associated with the valve means and responsive to the pressure of the steam at said source for preventing closing of the valve means when the pressure of the steam increases above a desired value, and means operative when the steam pressure is restored to the desired value of closing first that valve means whose temperature responsive means first demanded closing thereof.

11. In a temperature control system for a building having a plurality of zones to be conditioned, the combination of, a source of temperature changing fluid, means for supplying temperature changing fluid from said source to the zones of the building for conditioning the same, a valve for each zone for controlling the supply of temperature changing fluid to its associated zone, a two position electric motor for each valve for opening and closing the same and requiring electrical energy only when it is operating, power connections for supplying electrical energy to all of the electric motors, temperature responsive switching means associated with each zone, control connections between the temperature responsive switching means and the electric motor of each zone for opening and closing the valves of the various zones to maintain desired temperature conditions therein, and a relay including an operating winding located in the power connections in series with all of said motors and switches located in the control connections for preventing operation of any electric motor and its associated valve when any other electric motor and its associated valve are operating.

12. In a control system, the combination of, a plurality of electric motors, power connections for supplying electrical energy to all of said motors, a control device associated with each electric motor, control connections between the electric motors and the control devices whereby the electric motors are individually controlled by their associated control devices, and a relay including an operating winding located in the power connections in series with all of said motors and switches located in the control connections for preventing operation of any electric motor when any other electric motor is operating.

13. In a temperature control system for a building having a plurality of zones to be conditioned, the combination of, a source of temperature changing fluid, means for supplying temperature changing fluid from said source to the zones of the building for conditioning the same, valve means for each zone for controlling the supply

of temperature changing fluid to its associated zone, temperature responsive means associated with each zone for operating the valve means of that zone to maintain desired temperature conditions in the various zones, means associated with the valve means for preventing operation of any valve means while any other valve means is operating whereby the condition of the temperature changing fluid tends to remain at desired values, and means associated with the valve means and responsive to a condition of the temperature changing fluid affected by the demand for said fluid, said means being operative when the condition of the temperature changing fluid varies from the desired values to prevent operation of said valve means in a direction to cause said condition to vary further in the same direction, without changing the position of any valve means which has already operated in that direction.

14. In a temperature control system for a building having a plurality of zones to be conditioned, the combination of, a source of temperature changing fluid, means for supplying temperature changing fluid from said source to the zones of the building for conditioning the same, a valve for each zone for controlling the supply of temperature changing fluid to its associated zone, a two position electric motor for each valve for opening and closing the same and requiring electrical energy only when it is operating, power connections for supplying electrical energy to all of the electric motors, temperature responsive switching means associated with each zone, control connections between the temperature responsive switching means and the electric motor of each zone for opening and closing the valves of the various zones to maintain desired temperature conditions therein, a relay including an operating winding located in the power connections in series with all of said motors and switches located in the control connections for preventing operation of any electric motor and its associated valve when any other electric motor and its associated valve are operating whereby the condition of the temperature changing fluid tends to remain at desired values, control means responsive to a condition of the temperature changing fluid affected by the demand for said fluid, and switches operated by the control means and located in said control connections, said switches being operative when the condition of the temperature changing fluid varies from the desired values to prevent operation of said valve means in a direction to cause said condition to vary further in the same direction, without changing the position of any valve means which has already operated in that direction.

15. In a system of the class described, the combination of a plurality of electric motor driven valves for controlling the flow of fluid from a common source to a plurality of points of distribution, power connections for supplying electrical energy to all of said motors, a control device associated with each electric motor, control connections between the electric motors and the control devices whereby the electric motors are individually controlled by their associated control devices, and a relay including an operating winding located in the power connections in series with all of said motors and switches located in the control connections for preventing operation of any electric motor when any other electric motor is operating.

16. In a temperature control system for a building having a plurality of zones to be conditioned, the combination of, a source of temperature

changing fluid, means for supplying temperature changing fluid from said source to the zones of the building for conditioning the same, regulating means for each zone for increasing and decreasing the supply of temperature changing fluid to its associated zone, temperature responsive means associated with each zone for controlling the regulating means of that zone to maintain desired temperature conditions in the various zones, and means associated with the regulating means and responsive to the temperature changing capacity of the temperature changing fluid, said means being operative when the temperature changing capacity of the temperature changing fluid decreases below a desired value to prevent operation of any of said regulating means to increase the supply of fluid to its zone and when the temperature changing capacity increases above a desired value to prevent operation of any of said regulating means to decrease the supply of fluid to its zone, said last named means being ineffective to cause operation of any regulating means which has already operated to change the supply of fluid to its zone.

17. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, an outdoor controller for each zone including thermostatic means and temperature changing means, means associated with each zone and controlled by the thermostatic means of that zone for controlling the regulating means of that zone and the temperature changing means of the outdoor controller of that zone to increase the supply of temperature changing fluid and energize the temperature changing means and to decrease the supply of temperature changing fluid and deenergize the temperature changing means for the purpose of maintaining desired temperature conditions in the various zones and outdoor controllers, and means associated with all of said last mentioned means and responsive to the temperature changing capacity of the temperature changing fluid for preventing the associated regulating means for a given zone from either increasing the supply of temperature changing fluid or for causing energization of the temperature changing means of the controller for said given zone when the temperature changing capacity of the temperature changing fluid decreases below a desired value without causing the regulating means to decrease the supply of fluid if in fluid increasing condition or causing deenergization of the temperature changing means.

18. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, an outdoor controller for each zone including thermostatic means and temperature changing means, means associated with each zone and controlled by the thermostatic means of that zone for controlling the regulating means of that zone and the temperature changing means of the outdoor controller of that zone to increase the supply of temperature changing

fluid and energize the temperature changing means and to decrease the supply of temperature changing fluid and deenergize the temperature changing means for the purpose of maintaining desired temperature conditions in the various zones and outdoor controllers, and means associated with all of said last mentioned means and responsive to the temperature changing capacity of the temperature changing fluid for preventing the regulating means for any given zone from decreasing the supply of temperature changing fluid to said given zone and preventing deenergization of the temperature changing means of the zone controller for said given zone when the temperature changing capacity of the temperature changing fluid increases above a desired value without causing the regulating means to increase the supply of fluid if in fluid decreasing condition or causing energization of the temperature changing means if deenergized.

19. In a temperature control system for a building having a plurality of zones to be conditioned, the combination of, a source of temperature changing fluid, means for supplying temperature changing fluid from said source to the zones of the building for conditioning the same, regulating means for each zone for increasing and decreasing the supply of temperature changing fluid to its associated zone, an outdoor controller for each zone including thermostatic means and temperature changing means, controlling means associated with each zone and controlled by the thermostatic means of that zone for controlling the regulating means of that zone and the temperature changing means of the outdoor controller of that zone to increase the supply of temperature changing fluid and energize the temperature changing means and to decrease the supply of temperature changing fluid and deenergize the temperature changing means for the purpose of maintaining desired temperature conditions in the various zones and outdoor controllers, means associated with said last mentioned means and responsive to the tem-

perature changing capacity of the temperature changing fluid for preventing the regulating means from increasing the supply of temperature changing fluid and preventing energization of the temperature changing means when the temperature changing capacity of the temperature changing fluid decreases below a desired value and for preventing the regulating means from decreasing the supply of temperature changing fluid and preventing deenergization of the temperature changing means when the temperature changing capacity of the temperature changing fluid increases above the desired value, and further means associated with said controlling means

15 for preventing said associated means from changing the operation of said regulating means or from changing the condition of energization of said temperature changing means until the temperature changing fluid is of a value within said desired values.

20. In a temperature control system for a building having a plurality of zones to be heated, the combination of, a source of steam, heat exchanger means in each zone, means for supplying steam from said source to the heat exchanger means of the various zones for heating the same, valve means for each zone for regulating the supply of steam to the heat exchanger means of that zone, temperature responsive means associated with each zone for opening and closing the valve means of that zone to maintain desired temperature conditions within the various zones, means associated with the valve means and responsive to the pressure of the steam of said source for preventing opening of the valve means when the pressure of the steam decreases below a desired value and for preventing closing of the valve means when the pressure of the steam increases above the desired value, and further means associated with the valve means for preventing said last named means from changing the existing position of the valve means until the pressure of the steam is within said two desired values.

JOHN L. HARRIS.
